UNITED STATES PATENT OFFICE

2,611,079

DUPLEXING DEVICE FOR TRANSCEIVER
ANTENNA SYSTEMSArthur A. Varela and Robert A. Herring, Jr.,
Washington, D. C.

Application July 27, 1942, Serial No. 452,534

8 Claims. (Cl. 250—13)

(Granted under the act of March 3, 1883, as
amended April 30, 1928; 370 O. G. 757)

1

This invention relates broadly to an automatic coupling means for transceiver antenna systems and more particularly to a means facilitating the use of a single antenna in both the transmission and reception of radio echo waves.

In radio echo equipment for obstacle detection, wherein a short impulse is transmitted periodically and reflections of the impulse from obstacles are received at the same point, it is generally desirable to use the same antenna for both transmission and reception. This necessitates some means for automatically decoupling the receiver from the antenna during operation of the transmitter to prevent damage to the re-

quarter wave length and has each end shorted by a metal conductor. The inner conductor 9 is broken at its mid-point in order to form spark gap 7 and satisfy the aforementioned equation to produce maximum impedance change. A concentric line 8 will be used to couple the receiver to some predetermined point 5 on the tank 11. The concentric tank 11 is tunable upon adjustment of screw member 6.

The location of point 4 is selected as a function of the amount of power dissipated by gap 7 and point 5 is selected so as to establish a one-to-one coupling between lines 10 and 8 during the quiescent periods of gap 7.

On a received signal the impedances facing one another throughout the arrangement are matched and cause the tank to perform like a tuned transformer. The impedance of the tank rises gradually from a minimum at one end to a maximum at the gap 7 and then falls to a minimum at the other end. Gap 7 will function as a resonating capacitor between the two sections of the tank and assist in the production of a one-to-one coupling between points 4 and 5 as illustrated by the graph of Fig. 1a.

Upon operation of transmitter 3 gap 7 fires and forfeits its high impedance. The input impedance at point 4 will then diminish to some value $R+JX$. Subsequently the impedance at point 1 will increase by an amount sufficient to satisfy a characteristic impedance equation of a quarter matching section such as line 10. This increase of impedance at point 1 prevents a large amount of power from flowing into tank 11 from line 2. The voltage on the tank, in this case, will appear similar to that shown by Fig. 1b. It is therefore obvious that the coupling between points 4 and 5 has decreased considerably.

Fig. 2 shows an alternate method of decoupling the receiver from the antenna. Quarter wave line 10 joins the receiver line 8 and concentric tank 11 to the transmission line 2 at point 1. Upon the firing of the gap 7, series capacitor 12 resonates with the reactance of its lead and the tank. The voltage at 13 will then fall to some value lower than that at 14 resulting in a small ratio of coupling between the receiver and antenna. Whether there are any advantages of this arrangement over that shown in Fig. 1 depends mainly on the frequency, power and spark gap capacitance.

Another alternate arrangement is shown by Fig. 3. An auxiliary tank 11' is used to decouple the transmitter to prevent absorption of power during operation of the receiver. Lines 10 and 10' join their respective impedance tanks to transmission line 2 at points 1 and 1' displaced one from another by one-quarter wave length. The operation of tank 11' is similar to 11 in that it will offer a high impedance to the passage of low radio frequency voltages at point 1' when the gap 7' is conducting, and a low impedance when the gap is not conducting.

Although several embodiments of the present invention have been disclosed and described herein it is expressly understood that various changes and substitutions may be made therein without departing from the spirit of the invention as well understood by those skilled in the art. Reference therefore will be had to the appended claims for a definition of the limits of the invention.

The invention described herein may be manufactured and used by or for the Government of the United States of America for governmental

purposes without the payment of any royalties thereon or therefor.

We claim:

1. In a system having an antenna, a transmitter, a receiver and a transmission line coupling said transmitter to said antenna, means for coupling said receiver to said antenna and for automatically decoupling said receiver from said antenna during operation of said transmitter, said means comprising a section of concentric line having a metal conductor short circuiting each end thereof, input and output tap means located at different points along the axis of said line, the inner conductor of said line being broken at its mid-point to form a non-linear discharge device, means connecting said input tap means in parallel with said transmission line and means connecting said receiver to said output tap means.

2. In a system having an antenna, a transmitter, a receiver and a transmission line coupling said transmitter to said antenna, means for coupling said receiver to said antenna and for automatically decoupling said receiver from said antenna during operation of said transmitter, said means comprising a resonant concentric line section having a metal conductor short circuiting each end thereof, input and output tap means located at different points along the axis of said line, a spark gap formed at the mid-point of the inner conductor of said line, means connecting said input tap means in parallel with said transmission line and means connecting said receiver to said output tap means.

3. In a system having an antenna, a transmitter, a receiver and a transmission line coupling said transmitter to said antenna, means for coupling said receiver to said antenna and for decoupling said receiver from said antenna during operation of said transmitter, said means comprising a section of concentric line having a metal conductor short circuiting each end thereof, input and output tap means located at different points along the axis of said line to establish a one-to-one ratio of coupling therebetween on received signals, a spark gap formed at the mid-point of the inner conductor of said line, means connecting said input tap means in parallel with said transmission line and means connecting said receiver to said output tap means.

4. In a system having an antenna, a transmitter, a receiver and a transmission line coupling said transmitter to said antenna, means for coupling said receiver to said antenna and for automatically decoupling said receiver from said antenna during operation of said transmitter, said means comprising a section of concentric line having a metal conductor short circuiting each end thereof, input and output tap means located at different points along the axis of said line, a spark gap formed at the mid-point of the inner conductor of said line, a quarter wave matching line section connecting said input tap means in parallel with said transmission line and means connecting said receiver to said output tap means.

5. In a system having an antenna, a transmitter, a receiver and a transmission line coupling said transmitter to said antenna, means for coupling said receiver to said antenna and for decoupling said receiver from said antenna during operation of said transmitter, said means comprising coupling means from said transmission line to said receiver including a branch transmission line, a section of concentric line having a metal conductor short circuiting each end thereof, the inner conductor of said line being broken

at its mid-point to form a non-linear discharge device, input circuit means for said line and means connecting said input circuit means to said branch transmission line.

6. In a system having an antenna, a transmitter, a receiver and a transmission line coupling said transmitter to said antenna, means for coupling said receiver to said antenna and for automatically decoupling said receiver from said antenna during operation of said transmitter, said means comprising coupling means between said transmission line and said receiver including a branch transmission line, a quarter wave length of concentric line having a metal conductor short circuiting each end thereof, a spark gap formed at the mid-point of the inner conductor of said line, input tap means located at a point along the axis of said line and means connecting said input tap means to said branch transmission line.

7. In a system having an antenna, a transmitter, a receiver and a transmission line coupling said transmitter to said antenna, means for coupling said receiver to said antenna and for decoupling said receiver from said antenna during operation of said transmitter, said means comprising coupling means between said transmission line and said receiver including a branch transmission line, a section of concentric line having a metal conductor short circuiting each end thereof, a spark gap formed at the mid-point of the inner conductor of said line, input tap means located at a point along the axis of said line and means connecting said input tap means to said branch transmission line at a point thereon spaced from said transmission line by a distance equal to a quarter wave length of the frequency of said transmitter.

8. In a system having an antenna, a transmitter, a receiver and a transmission line coupling said transmitter to said antenna, means for coupling said receiver to said antenna and for automatically decoupling said receiver from said antenna during operation of said transmitter, said means comprising a section of concentric line

having a metal conductor short circuiting each end thereof, a spark gap formed at the mid-point of the inner conductor of said line, input tap means located at a point along the axis of said line, a quarter wave length line section having one end thereof connected to said transmission line, means including a capacitance joining said input tap means to the other end of said quarter wave line section and means connecting said receiver to said quarter wave line section.
